UNITED STATES PATENT OFFICE

1,923,874

ELECTRIC HEATER

John C. Morgan, Los Angeles, Calif.

Application March 15, 1928. Serial No. 261,817

7 Claims. (Cl. 219—34)

This invention relates more particularly to a foldable electric heater.

The general object of my invention is to provide an electric heater which may be readily knocked down and folded into a small compact bundle for carrying and shipping purposes. I thereby provide a novel device that may be conveniently packed in a grip and carried from place to place and unfolded and set up for use when desired.

A more particular object is to provide a novel electric heater of the character stated which will be simple in construction, economical and highly practical and efficient in operation, and which may be easily and quickly collapsed and set up.

The invention is particularly useful for travelers who may go from place to place and find accommodations insufficiently heated or not heated at all; and an object of my invention is to provide a novel heater that may be conveniently carried by such travelers and attached to the usual electric light socket or plug for heating purposes.

Other objects, advantages and features of invention may appear from the accompanying drawings, the subjoined detail description and the appended claims.

The accompanying drawings illustrate the invention in a form I at present deem preferable.

Figure 1 is a front elevation of an electric heater embodying my invention and shown in unfolded position ready for use.

Fig. 2 is a side elevation of the heater shown in Fig. 1.

Fig. 3 is a front elevation detail view of the heater reflector in folded and detached position.

Fig. 4 is an edge view of the detached folded reflector shown in Fig. 3.

Fig. 5 is an elevation of the heater stand in folded position.

Fig. 6 is a horizontal section of the stand taken on line 6—6, Fig. 5 looking in the direction of the arrows.

Fig. 7 is a side elevational view of the heater guard shown detached and in folded position.

Fig. 8 is a fragmentary sectional view of adjacent sector plates of the reflector and one guard wire taken on line 8—8, Fig. 2, looking in the direction of the arrows.

Fig. 9 is a fragmentary rear view of adjacent sector plates of the reflector in unfolded position showing the means for holding said sector plates together and in unfolded position.

Fig. 10 is a fragmentary longitudinal section

of the folded reflector sections taken on line 10—10, Fig. 3.

Fig. 11 is a fragmentary sectional view taken on line 11—11, Fig. 9.

My invention comprises generally a foldable stand 1, a foldable reflector 2, and a foldable guard 3.

The stand 1 comprises a standard 4, legs 5, preferably three in number, a spider 6 slidably mounted on said stand and to which spider said

legs are pivoted at 7 by any suitable means, such as the rivets shown; and also includes on the lower end of said standard, spring locking means 8 for the legs 5.

The spider 6 is formed with a depending sleeve 9 which slidably surrounds the standard 4 and said sleeve is provided with bayonet slots 10 and may be formed on its lower end with strengthening means in the form of an external flange 11 which is provided with slots 12 in registration with the bayonet slots 10.

The locking means 8 comprises a pair of collars 13 and 14, a spring 15 surrounding the standard 4 and operating between said collars 13 and 14, and a pair of pins 16 and

17 extending through the standard and against which pins the spring 15 normally urges and holds the collars 13 and 14.

The upper end 18 of the standard 4 is provided with a fork 18 through which extends a bolt 19 of any suitable design, the head 19a of which engages one member of said fork, while a butterfly nut 20 screws on the end of said bolt against the other fork member.

The inner ends 5a of the legs 5 are inclined for engaging the inner ends 6a of slots 6b formed in the spider 6 and in which slots

said legs are pivoted.

The reflector 2 comprises a central mounting 21 and a plurality of concave-convex sector plates 22 pivotally mounted on said mounting.

The mounting 21 preferably comprises a tube 23 provided with an external shoulder 24 formed on its inner end, a washer 25 surrounding the outer portion of said tube, and an endwise adjustable ring 26 detachably secured on the outer end of said tube by means of screws 27.

The plates 22 are formed with central openings 28 through which the tube 23 extends with the plates arranged in super-imposed relation.

The innermost plate engages the shoulder 24 and the outermost plate being engaged by the washer 25 and held in frictional engagement therewith by ring 26, whereby the plates are

turnably and detachably mounted on the mounting 21. The washer 25 is formed at its lower

80

85

90

95

100

105

110

edge with supporting means, such as a knuckle 29 adapted to fit within the fork 18 and to receive the bolt 19. A circular handle 30 is hinged to the upper edge of the washer 25, at 30a and said handle 30 is adapted when folded to encircle the tube 23 as shown in Fig. 3 and Fig. 10. The outermost plate 22' is provided in its outer corners with slots 31 and 32 while headed pins 33 and 34 are secured to the outer side of the innermost plate 22" in the respective outer corners thereof. The remaining plates 22 are each provided in one outer corner with a slot 32' and a headed pin 34' is secured in the other outer corner and to the outer side thereof. The slots 31, 32, and 32' are enlarged at one end as at 35 to permit the heads of the pins 33, 34 and 34' to be inserted therethrough.

The foldable guard 3 comprises a central tie ring 36 and a plurality of openings 38 to receive closed hooks 39 on the upper ends of the guard wires 37 whereby said wires are pivotally and foldably connected to the ring 36. The outer ends of the guard wires 37 are bent outwardly and backwardly to form V-shaped engaging members 40 the extremities of which members being bent outwardly and upon themselves into stops 41.

My heater employs a suitable electric socket 42, plug 43, wires 44 and 45 and any suitable electrical unit, such as a heating coil 46 which fits into said socket.

My heater is unfolded and set up as follows:

Referring first to Fig. 5 in which the stand 1 is shown folded, the spider 6 and sleeve 9 are first slid down the standard until the flange 11 engages the washer 14 and compresses the spring 15, the pin 17 passing through the slots 12 in the flanges 11 into the entrance of the bayonet slots 10. The spider 6 and sleeve 9 are then turned until the pin 17 interlocks with the bayonet slots 10 as shown in Fig. 1, thus detachably securing the spider to the lower end of the standard 4 by the leg securing means 8. The legs 5 are then unfolded until their inner ends 5a engage the inner ends of the spider slots 6b whereby the legs are held in standard supporting position as shown in Figs. 1 and 2.

Referring to Figs. 3 and 4 in which the reflector is shown folded, the plates 22 are turned in the mounting 21 until the adjacent edges thereof overlap each other with the pin 33 in register with the enlarged end 35 of slot 31 and the pin 34 in register with the enlarged end 35 of a slot 32' respectively. The pin 33 is then inserted through the enlarged end 35 into slot 31 and the pin 34' inserted through the enlarged end 35 of slots 32 and 32'. The plates 22 are turned away from each other until a pin enters and engages the small end of a slot with the heads of the pins engaging the outside of the plates 22, 22' and 22" as illustrated in Figs. 1, 2, 9 and 11, thus holding the reflector in unfolded position.

The butterfly nut 20 is removed from the end of the bolt 19 and the bolt withdrawn through the fork 18. The knuckle 29 is then placed in the fork 18 and the bolt 19 inserted through the fork and said knuckle. The reflector is adjusted on said bolt to the proper angle and the nut 20 is screwed on the threaded end of the bolt 19 against one member of the fork 18 until the knuckle is clamped firmly in the fork thus detachably securing the reflector on the stand at the proper angle (see Fig. 2).

Referring to Fig. 7 the guard wires 37 are

then swung to unfolded position and their engaging members 40 inserted from the inside of the reflector through the enlarged ends 35 of the slots 31, 32 and 32' respectively with said members engaging the edges of the plates 22 and holding them under tension in unfolded position (see Figs. 1, 2, 8, and 9). This construction maintains the reflector in circular position and prevents accidental disengagement of the reflector sector plates.

The socket 42 is then inserted through the mounting tube 23 into the reflector and is fitted in said tube where it may be retained by further tightening of a screw 27. The electrical unit or heating coil 46 is then screwed or otherwise secured into the socket 42 and upon inserting the plug 43 into a service socket, electric current is supplied to the coil 46 and the heater is put in operation.

To collapse or knock down and fold up the heater the above described operations are reversed.

By the foregoing construction I am able to construct an electric heater having a 10 inch reflector and collapse the same into a small compact package having approximately the following dimensions, to wit; three inches in width, by seven inches in length, and five inches in depth.

I claim.

1. As an article of manufacture, a reflector comprising a mounting; a plurality of reflector sections turnably mounted on said mounting so that they may be folded into superimposed relation and unfolded around said mounting, said sections being provided with cooperating slots and pins at their outer corners for engagement with each other to hold the edges of said sections together.

2. In an electric heater, a reflector comprising a mounting; a plurality of reflector sections turnably mounted on said mounting so that they may be folded into superimposed relation and unfolded around said mounting so that the edges on adjacent sections overlap, said sections being provided with cooperating slots and pins for engagement with each other to hold the overlapping edges of said sections together, said slots being enlarged at one end to permit entrance to and exit from said slots of said pins.

3. In an electric heater, a reflector comprising a mounting, a plurality of reflector sections connected to said mounting so that they may be folded into superimposed relation and unfolded to constitute a circular shade, said sections being provided with a slot adjacent one corner thereof; and a guard for said reflector comprising a tie member and a plurality of guard wires foldably connected at one end to said member and being adapted at their other end to be inserted into said slots to prevent accidental movement of said reflector sections relative to each other.

4. In an electric heater, a reflector comprising a mounting, a plurality of reflector sections connected to said mounting so that they may be folded into superimposed relation and unfolded to constitute a circular shade; means comprising co-operating slots and pins for securing the outer edges of said sections in unfolded position, and a guard for said reflector comprising a tie member and a plurality of guard wires foldably connected at one end to said member and being adapted at their other end

to be respectively inserted in a slot in said sections and adapted to prevent accidental movement of said sections relative to each other.

5. In an electric heater, a reflector provided with slots; a reflector guard comprising a ring; a plurality of guard wires foldably connected at one end to said ring; and stops in the free ends of said guard wires adapted to be inserted in the slots in said reflector under tension to 10 retain said guard in position.

6. In an electric heater, a reflector comprising a mounting; a plurality of reflector sections turnably mounted on said mounting so that they may be folded into superimposed 15 relation and unfolded around said mounting into a circular reflector, said sections being provided with cooperating slots and pins at ad-

jacent edges of said sections for engagement with each other to hold said sections together; a guard for said reflector comprising a plurality of guard wires arranged to project into one end of said slots for locking said sections against accidental rotary movement on said mounting.

7. The combination of a reflector comprising a mounting adapted to receive an electrical unit, and a plurality of reflector sections connected to said mounting and adapted to be folded into superimposed relation and unfolded around said mounting; means to support said reflector; and a handle member pivotally connected to said mounting, said handle being adapted to be moved into folded position to encircle said 90 mounting.
